UNITED STATES PATENT OFFICE.

WILLIAM LYON KINSLEY, OF LOWELL, VERMONT.

BELT-FASTENER.

SPECIFICATION forming part of Letters Patent No. 434,636, dated August 19, 1890.

Application filed December 16, 1889. Serial No. 333,920. (No model.)

To all whom it may concern:

Be it known that I, WILLIAM LYON KINSLEY, a citizen of the United States, residing at Lowell, in the county of Orleans and State 5 of Vermont, have invented certain new and useful Improvements in Belt-Fasteners; and I do declare the following to be a full, clear, and exact description of the invention, such as will enable others skilled in the art to 10 to which it appertains to make and use the same, reference being had to the accompanying drawings, and to the letters of reference marked thereon, which form a part of this specification.

15 My invention has relation to belt-fasteners; and it consists in the improved construction and combination of parts, as hereinafter more fully pointed out, whereby I provide a device of this character combining both lightness 20 and durability, together with the effectiveness of operation, and, furthermore, a construction whereby the clamping-plates employed by me in connection with the coupling-link are retained securely in place.

25 In the accompanying drawings, forming part of this specification, Figure 1 is a perspective view of my improved belt-fastener, showing the ends of the belt secured therein. Fig. 2 is a perspective detail view of one of the clamping-plates. Fig. 3 is a detail view of the coupling-link used in conjunction with the clamping-plates. Fig. 4 is a bottom view of my improved fastener with the ends of the belt removed therefrom, and Fig. 5 is a cross-sectional 30 view taken on the line $x-x$, Fig. 1.

35 Like letters of reference refer to like parts throughout the several views.

Referring to the drawings, the letter A indicates the coupling-link, of wrought-iron or 40 other suitable material, rectangular in shape and provided with end pieces a, a and a transverse central strengthening-piece a' . The side pieces of this link are provided upon their inner edges with inwardly-extending 45 lugs or projections a^2 , arranged at suitable intervals apart.

The letters B B indicate two homogeneous clamping-plates, said plates being S-shaped in cross-section and provided at their upper 50 edges with lateral inwardly-extending teeth b , and also having their ends provided with horizontal notches b' , which are designed to

engage the end pieces of the link when the plates are adjusted between the same. These plates are further provided with a series of 55 apertures b^2 , preferably rectangular in shape and adapted to receive the correspondingly-shaped lugs or projections a^2 of the link. In this manner, and in conjunction with the end horizontal notches, the clamping-plates are 60 securely retained in position.

In order to effect the insertion of the plates within the link, it is necessary to provide the same with central vertical notches b^3 b^3 , into which fit the transverse central strengthening-piece of the link.

In operating my improved belt-fastener I first form slots in the ends of the belt desired to be connected together to correspond with the width of the transverse strengthening-piece 70 of the link. I then, after first inserting the clamping-plates within the coupling-link, pass the ends of the belt through from the under side of the fastener, the ends thereof projecting above the top of the clamping-plates. It 75 is now only necessary that a slight force be exerted upon the belt proper. The projecting ends of the belt are then cut off within a short distance of the clamping-plates, as shown in Fig. 1 of the drawings. It will be readily 80 observed that the greater the strain exerted upon the belt the tighter will be the binding thereof, as the outward pressure upon the curved bottom of the clamping-plates necessarily produces an inward pressure of 85 the upper edges of said plates. It is also obvious that by this construction of belt-fasteners, I am enabled to secure the ends of the belt instantly, and thus save considerable time in adjustment, which has heretofore 90 been found a difficulty in devices for analogous purposes.

An important advantage of my device is the security with which the clamping-plates are held in position within the link, the apertures in said plates, in connection with the lugs or projections firmly holding the sides thereof, while the end horizontal notches engage the end pieces of the link, firmly supporting the end portions of the plates. It is 95 100 of course preferable that the inwardly-extending lugs only extend flush with the inner edge of the apertures which they engage, so as to obviate any danger of the ends thereof

coming in contact with the belt and puncturing or injuring the same.

- The end horizontal notches above referred to not only serve as supports for the plates 5 when the belt is adjusted between the same, but, furthermore, when the belt is removed the plates are still retained in position through the medium of these notches, as well as the inwardly-projecting lugs.
- 10 In devices of this character as heretofore constructed no means have been shown for holding the plates in position after the ends of the belt have been removed, and said plates are free to fall, occasioning considerable 15 trouble and annoyance. By the construction employed by me, however, this difficulty is obviated, and if it is found desirable for any reason to remove the plates all that is necessary to be done is simply to adjust them to 20 an oblique position with reference to the link, so that the ends of the plates will be in the corners or angles of said link. In this position they may be readily removed.

It is obvious that, if preferred, the upper 25 toothed or serrated edges of the plates may be dispensed with, as the concave formation of the upper part of the plates is sufficient to hold the ends of the belt from slipping.

My invention, furthermore, is exceedingly 30 simple in construction and little liable to breakage, owing to the severe tension of the belt exerted upon the clamping-plates, which in turn bear upon the side pieces of the link, the latter being strengthened by the central 35 transverse strip.

Having thus fully described my invention, what I claim, and desire to secure by Letters Patent of the United States, is—

1. In a belt-fastener, the combination, with 40 clamping-plates substantially S-shaped in cross-section, whose clamping edges are rough-

ened or serrated and adapted to receive the ends of the belt between the inner faces thereof, and also provided with a series of apertures, of a coupling-link provided with 45 a series of inwardly-extended teeth passing into the apertures of the clamping-plates, the inner ends of said teeth being flush with the inner edges of the apertures in the clamping-plates, substantially as set forth.

2. In a belt-fastener, the combination, with a coupling-link provided with a series of inwardly-extending lugs or projections and a central strengthening-piece or cross-bar, of clamping-plates inserted between the sides 55 of the link, said plates being substantially S-shaped in cross-section and provided with central notches, into which fit the central strengthening-piece, and also provided near their upper convex edges with a series of apertures adapted to receive the inwardly-extending lugs or projections, substantially as set forth.

3. In a belt-fastener, the combination, with the herein-described coupling-link provided 65 with a transverse strengthening-strip, of clamping-plates substantially S-shaped in cross-section, provided at their upper edges with lateral inwardly-extending teeth, and also provided with vertical notches for the 70 reception of said strengthening-piece, and having end horizontal notches to receive the end pieces of the coupling and support the plates in position within the same, substantially as set forth.

In testimony whereof I affix my signature in presence of two witnesses.

WILLIAM LYON KINSLEY.
